UNITED STATES PATENT OFFICE.

JOHN SUTINEN, OF DULUTH, MINNESOTA.

RAILROAD TIE.

Application filed May 16, 1927. Serial No. 191,564.

This invention relates to railroad ties and has special reference to such ties made of sheet metal, such as steel or the like, the principal object being to produce a more 5 practical and efficient pressed steel tie than heretofore known.

Another object is to produce a form of such ties suitable for use on a gravel or like roadbed and also upon fabricated structures, such as trestles, bridges, or the like.

Other objects and advantages of the peculiar structure will appear in the further description thereof.

Referring now to the accompanying drawing, forming part of this application, wherein like reference characters indicate like parts:

Figure 1 is a perspective view of the body portion of one of the improved ties particularly adapted for use upon a fabricated 20 structure;

Figure 2 is a perspective view of one of the removable block housings for either end of the tie;

Figure 3 is a horizontal sectional view 25 through one of the housings as applied to the tie;

Figure 4 is a plan view of one end of the tie turned in the opposite direction to that shown in Figure 3 with the block within 30 the housing and a common rail plate on the block;

Figure 5 is an elevation of one end of a tie having a rail mounted thereupon, and the former mounted upon a wooden fabricated 35 structure;

Figure 6 is a central vertical section through one of the end housings as applied to a tie having a block therein and a rail mounted thereon, the tie being mounted upon 40 a metal fabricated structure;

Figure 7 is a view of a tie similar to Figure 1 except that this tie is particularly adapted for use on the ordinary road bed;

Figure 8 is an elevation of one of the ties 45 shown in Figure 7 with the block housings attached thereto and railroad rails mounted thereupon;

Figure 9 is a top plan view of Figure 8;

Figure 10 is a perspective view of a shimming wedge; and

Figure 11 is a perspective view of a rail holding dog.

The function and operation of the two different ties shown, for example in Figures 1 55 and 7, are substantially identical except that shown in Figure 7 is provided with addi-

tional holding lugs 9, and is somewhat larger for use upon common roadbeds; and the other shown in Figure 1 is somewhat smaller, being especially adapted for use on a fabricated structure such as a trestle, bridge, or the like, as previously explained.

The tie is of right angular form in cross section and preferably the length of the ordinary railroad tie, and in both forms here shown is provided with notches spaced inwardly of their ends as illustrated at 1 to register centrally of the rails of the common railroad track; these notches being for co-operation with a rail wearing plate when used or for providing clearance between the rail base and the edge of the tie. In Figure 6 the rail plate 2 is shown resting within the notch at one end and its other end resting within a somewhat similar notch 3 in the outer side of the block housing, as shown in Figure 2 in this instance being formed by first cutting at both ends and then striking downwardly at right angles a lip-like projection 4 which provides a wide and substantial support for the outermost end of the rail plate 2.

The form of tie shown in Figure 7 of the drawings is also provided with long notches 5 in the base flange 6 of same, while the notches 1 above referred to are in the upright flange 7, and these notches or recesses 5 are provided for the reception of the lower outermost wall 8 of the block housings as the latter are made of uniform size for both sizes of ties and in the case of the tie shown in Figure 7 which has a wider base than those shown in Figure 1 as previously set forth necessitates such notching, and not only that but provides more positive registration for the block housings on this type of tie which is the form used on a more yielding roadbed than that upon which the tie illustrated in Figure 1 is employed.

The upright wall 7 of the tie shown in Figure 7 is provided with L-shaped lugs 9, turned outwardly in respect to the tie adjacent each one of the notches or recesses 1, such lugs being for overlapping registration with other of the rail holding attachments to be subsequently described.

The rectangular block housings are formed with wing like lugs 10 upon either innermost extremity thereof, they being turned at right angles to the ends 11 and provided with suitable holes for bolting to the upright wall or member of the tie.

They are also provided with similarly shaped inwardly turned lugs 12 for overlapping engagement with wooden blocks 13 which are installed within the housings for a 5 more yieldable bearing for the rail than were the latter allowed to rest directly upon metal portions of the tie assembly. These housings also have an inwardly projecting right angled portion 14 which in the event 10 of association with the tie shown in Figure 1 abuts directly against the back edge thereof as clearly shown in Figure 3 of the drawing, but when used in connection with the tie shown in Figure 7 for the common roadbed 15 the wall 8 registers within the recess 5 in said tie and the projection 14 underlaps same as clearly seen in Figure 8 of the drawings. In either event it is obvious that the wooden block for the support of the rail is firmly 20 held within the housing, the latter of course being bolted in any desired manner with suitable through bolts as indicated at 15, and in the event of the rails being mounted upon wearing plates as indicated at 2 on these 25 blocks 13 they may be spiked directly to the wooden blocks, and in some instances this form of mounting may be resorted to exclusively. However I prefer to have associated with a portion at least, if not all, of 30 such ties an anti-spreading bar such as indicated at 16 for attachment to the upper outer edge of the upright portion of the tie, said bar being bolted to the tie in any desired manner by suitable through bolts 17, 35 the centermost one of which I prefer to have mounted within a vertically slotted hole in the tie wall to provide desired adjustment of either end of the bar independently. The outermost ends of these bars are turned inwardly as at 18 for proper registration with the outer base flange and web of the railroad rail as clearly illustrated, and not only act as an anti-spreading means but also adequate supports for the rail to prevent its tipping 40 over as for instance on a curve or the like. In conjunction with the bar 16 are provided dogs 19 having an elongated body portion for bolting engagement externally of the bar 16 as well as through the upright 45 flange of the tie, there being one adjacent

either end of the bar 16 and each provided with a suitably shaped nose for overlapping engagement with the inner base flange of the rail. As before stated, these dogs may or may not be used either with the bar 16 or 55 without them as circumstances may require and in the event of the dogs or the inwardly turned portions 18 of the bar 16 requiring tightening in respect to the rail, I provide wedge shaped shims 20 as illustrated in Figure 10 of the drawings, these being sufficiently thin and long to be driven intermediate of the base of the rail and either of the engaging portions above referred to and the end bent up as by a chisel or the like to 60 prevent their jarring loose.

In the forming of the dogs 19 they may be struck from sheet metal and provided with an upper inwardly projecting lug 21 and a lower inwardly projecting lug 22 for 65 overlapping engagement with the edges of the bar 16, thus affording a more positive union with said bar when bolted thereto.

Having thus described my invention, what I claim and desire to secure by Letters Patent, is:

1. A railroad tie comprising an angle bar having rail plate engaging recesses in one edge thereof, housings secured to the angle bar, and a wooden block within each housing, each rail being attached to a block registering within a recess.

2. A railroad tie of the type described comprising an angle bar, rail supporting housings secured to the bar adjacent either end thereof, an anti-spreading member removably attached to the bar and engaging the rails upon the outer sides thereof, and dogs attached to the angle bar through the anti-spreading member for engaging the rails upon the inner sides thereof.

3. A railroad tie comprising a single L-shaped angle bar, a housing fitting within the angle of said bar secured to the upright flange thereof and resting upon the horizontal, and resilient means within the housing to which the rails are secured.

In testimony whereof I affix my signature.

JOHN SUTINEN.
